FEELER MECHANISM FOR WEFT-REPLENISHING LOOMS.

1,084,124.

Specification of Letters Patent. Patented Jan. 13, 1914.

Application filed October 18, 1912. Serial No. 726,476.

To all whom it may concern:

Be it known that I, EUGENE H. BALLOU, of Pawtucket, in the county of Providence and State of Rhode Island, have invented certain new and useful Improvements in Feeler Mechanism for Weft-Replenishing Looms, of which the following is a specification.

The present improvements consist in a new feeler mechanism for weft-replenishing looms which detects the approaching exhaustion of the weft within the running shuttle and initiates the weft-replenishing action so that the weft-replenishment is completed before the weft within the shuttle is completely exhausted, thus enabling perfect cloth to be woven.

In accordance with the present invention there are two feelers which both enter the shuttle and come in contact with the mass of weft therein. These feelers are so related to each other and to the remaining mechanism, that the primary feeler is moved into inactive position with respect to the mechanism controlled by the feelers each time that it comes in contact with an ample quantity of the weft, but, when the exhaustion of the weft approaches the critical stage, this primary feeler is not moved to inactive position by reason of the peculiar character of the weft-carrier within the shuttle, and, as a result, the weft-replenishing action is initiated. Also, there is a third feeler which can be adjusted so as to come in contact with a definite datum surface, such as the front wall of the shuttle, when the weft approaches exhaustion thereby rendering the primary feeler active and hence instituting the replenishing action. This third feeler is employed in case weft-carriers of usual construction are alone available, and may be employed when the special weft-carriers are used.

The present improvements are illustrated in the accompanying drawings, wherein—

Figure 1, is a plan view of portions of the lay and breast-beam of a loom, at the detecting side of the loom. Fig. 2, is a vertical longitudinal section in the plane indicated by the line 2—2 in Fig. 1. Fig. 3, is a vertical transverse section showing the feelers in normal idle position. Fig. 4, is a section like Fig. 3, but showing the primary feeler inactive. Fig. 5, is a section like Fig. 3, showing the primary feeler in action. Figs.

6, 7, and 8, are detail sections in the planes indicated by the lines 6—6, 7—7 and 8—8, respectively, in Fig. 1.

The drawings illustrate only sufficient of the loom to enable the present improvements to be understood. They show the shuttle-box A, on the lay at the detecting side of the loom; the shuttle B, within the shuttle box A; a weft-carrier C, within the shuttle carrying a supply of weft D; a portion of the breast-beam E; and the rocking change shaft F, which is rocked when the weft-replenishing action is initiated and which controls the weft-replenishing devices in a now well-known way, this change shaft corresponding, for example, with the rock shaft shown at ^d in United States Letters Patent of Northrop, No. 600,016, March 1, 1898.

The front wall of the shuttle and the front wall of the shuttle-box are slotted as indicated at *a*, for the entrance of the feelers G, H, both of which enter the said slots and contact with the weft D. The feeler H, is herein called the "primary" feeler because it projects rearwardly (that is, toward the weft D,) beyond the "secondary" feeler G, and hence comes in contact with the weft in advance of the secondary feeler. There is a third feeler I, which is so adjustable that it can be used or not, as desired. When used it comes in contact with a definite datum surface, such as the front wall of the shuttle. It will hereinafter be called the "auxiliary feeler." The mechanism will first be described, on the assumption that the auxiliary feeler is adjusted forwardly so as to have no effect. Its useful adjustment will subsequently be explained.

Both of the feelers G, and H, are connected so as to reciprocate when acted upon by the weft. The primary feeler H, is mounted upon the secondary feeler G, so as to move therewith. The secondary feeler G, has a forwardly extending shank J, which is slidably mounted within a guide K, fastened to an extension of the breast-beam E. A coiled spring L, (Fig. 3) within the guide K, bears against a shoulder *b*, on the shank J, to move the feelers G, and H, rearwardly toward the shuttle box. When the shuttle is within the shuttle-box A, at the detecting side of the loom, and the lay then beats forwardly, the feelers G, and H, registering with the slots *a*, are encountered by the weft D, and are forced forwardly against the ten-

sion of the spring L, during the remainder of the final beat of the lay. When the lay again recedes, the spring L, restores the feelers G, and H, to their normal rearward position. In addition to this reciprocating movement which the primary feeler H, has in common with the secondary feeler G, it has an independent movement of its own. The feeler H, reciprocates with respect to the feeler G. The feeler G, surrounds the feeler H, at its rear or feeling end, (Figs. 4, and 5,) so as to furnish a guide therefor. At its forward end, the feeler H, is pivotally connected to the lower arm c, of a lever which is adjustably and pivotally connected at d, to a bracket e, on the shank J, of the feeler G. This lever has a long forwardly extending arm f, the weight of which tends normally to cause the feeler H, to project rearwardly beyond the feeler G, and nearer the weft D, as shown in Figs. 1, 3, and 5.

When the lay beats forward with the shuttle in the shuttle-box A, at the detecting side of the loom, the weft D, first comes in contact with the rearwardly projecting primary feeler H, causing it to slide forwardly upon the feeler G, thereby lifting the forwardly extending weighted arm f, of the lever c, f, as shown in Fig. 4; and immediately thereafter the weft encounters the rearward end of the secondary feeler G, and during the remainder of the forward beat of the lay, both feelers move forwardly together against the stress of the spring L.

When the lay retreats, both feelers move rearwardly together under the stress of the spring L, and the primary feeler H, moves still farther rearwardly on account of the weight of the arm f, of the lever c, f. This action continues until the supply of the weft D, becomes so far reduced as to demand weft-replenishment. When this critical point is reached, (assuming the auxiliary feeler I, to be out of action), the primary finger H, does not come into effective contact with the weft in substantial advance of the secondary feeler G, so that both feelers move forward substantially together and the feeler H, does not slide upon the feeler G, and consequently the forwardly extending arm f, starts the weft-replenishing mechanism into action, since it maintains its lowermost position. The retention of this lowermost position by the arm f, starts the weft-replenishing mechanism into action, but before the controlling mechanism is described attention will be directed to the peculiar construction of the weft-carrier C, which permits this concurrently effected movement of both feelers.

The weft-carrier C, at its portion which registers with the primary feeler H, is formed with longitudinal grooves or flutes g, as shown in Figs. 1, 3, 4 and 5, these flutes being located all the way around the weft-

carrier C, so that one of them is always opposite the primary feeler H. These grooves or flutes are similar in function to those described in United States Letters Patent of Northrop, No. 686,903, November 19, 1901. When the weft approaches exhaustion, the primary finger H, (which is thin at its feeling end) crowds the weft into one of these flutes or grooves, (Fig. 5,) so that, finally, the primary finger H, does not come in contact with the weft in substantial advance of the finger G, and hence both fingers move forwardly together and there is no independent sliding of the primary feeler on the secondary feeler. As already stated, the result of this failure of the primary finger to slide upon the secondary finger is to leave the arm f, in its normal lower position, at which time a pin h, (carried by it) rests (Figs. 1, and 3,) upon a controller M, which is a lever pivoted at i, to an extension of the breast-beam. The arm f, has a tooth l, on its lower face which, normally, (that is, when the feelers are at rest), is just back of the rear upper corner of a ledge m, on the controller M. When the weft encounters the primary finger H, in advance of the secondary feeler G, during the forward swing of the lay this tooth l, of the arm f, is lifted above the ledge m, so that said tooth rides forwardly clear above the ledge, as indicated in Fig. 4. When, however, due to the approaching exhaustion of the weft, the arm f, is maintained in its lower position the tooth l, encounters the ledge m, as the two feelers move forward with the result that the controller M, is swung on its pivot l.

The controller M, has a short arm p, which is pivotally connected with a slide O, which carries a cam r, as shown in Fig. 2. Normally a dagger P, rests upon the high part of this cam r. This dagger P, as shown in Fig. 8, extends forwardly horizontally above the breast-beam and is pivotally connected at its forward end with a vertically extending arm Q, which is secured fast to the rocking change shaft F. Normally, this dagger P, is held by the cam r, above the path of a vibrating weft hammer R, which is reciprocated in the usual way. When, however, the controller M, is swung (owing to the tooth l, encountering the ledge m,) the cam r, is withdrawn from the dagger P, whereupon said dagger drops into the dotted line position shown in Fig. 8, where it is in the path of the vibrating weft-hammer. Accordingly, at its next forward stroke, the weft-hammer encounters the dagger P, moving it forwardly, thereby rocking the change shaft F, and bringing about the weft-replenishment in a well-known way.

After the replenishment has been effected, a spring t, (Fig. 6,) restores the controller M, and the cam slide O, to their normal positions, and the change shaft F, with its con-

neeted parts are restored to their normal positions in the usual way.

The primary feeler H, is adjustably located and guided on the secondary feeler 5 G, so that the rearward projection of the primary feeler beyond the secondary feeler can be regulated, so as to insure correct action. For this purpose the pivot pin d, for the lever e, f, is eccentrically located 10 on a disk u, which turns within a split bearing v, on the bracket e, said disk being clamped in any position of adjustment by the screw bolt w, as shown in Fig. 4.

The forward reciprocation of the feeler 15 H, is limited by a stop x, on the feeler G. The feeler H, is loose vertically within the guide at the rear end of the feeler G, as shown in Figs. 4, and 5, thereby having a rising and falling capability within the 20 guide, thus permitting the feeler H, to rise and enter a flute g, in case a rib between two flutes is in the direct path of the feeler H.

Both of the feelers G, and H, encounter 25 the weft, thus avoiding disturbance which may be caused by variations in shuttles, weft-carriers, and their relative positions, but special fluted weft-carriers are required. Hence, the "auxiliary feeler" I, is employed which enables the loom to be used 30 with ordinary unfluted weft-carriers.

The auxiliary feeler I, screws into a bracket y, fast on the feeler G, and is held in its adjusted position by a lock nut z, 35 as shown in Fig. 4. The feeler I, does not contact with the weft but with a definite datum surface such as the front wall of the shuttle. When adjusted to active position 40 the feeler I, encounters the shuttle before the feeler H, can be reciprocated by the weft with the result that the shuttle pushes the feelers G, I, forward with the lever arm f, in its lower position thus initiating the weft-replenishing action.

The feeler G with its shank J serves as a 45 feeler support for the primary feeler H, and the auxiliary feeler I, and for the actuator consisting of the lever e, f, which actuates the controller M, when the weft-replenishing mechanism is to be set into action.

When the auxiliary feeler I is in action no 50 part of the pressure applied to the spring L (which moves the feeler support toward the lay) by the lay is transmitted through the primary feeler. The only force exerted by the bobbin as the lay moves forward is 55 that required to push forward the primary feeler and lift the front end of the actuator.

The entire work of pushing the feeler support and the parts carried thereon forwardly against the tension of the spring L is transmitted by the lay through the auxiliary feeler I. Consequently, there is no strain tending to displace the bobbin within 60 the shuttle and, accordingly, the amount of

waste weft is reduced to a minimum, close setting of the auxiliary feeler being permissible.

I claim—

1. A feeler mechanism for a weft-replenishing loom having, in combination, a primary feeler and a secondary feeler, which both enter the shuttle and come in contact with the mass of weft therein; a guide in which the secondary feeler reciprocates; a spring acting on the secondary feeler to move it toward the lay; a guide on the secondary feeler within which the primary feeler has an independent sliding movement of its own, and a rising and falling capability, said primary feeler normally projecting rearwardly beyond the secondary feeler so as to contact with the weft in advance of the secondary feeler, and the contacting end of said primary feeler being thin so as to force the weft into a groove of a fluted weft-carrier; a lever adjustably pivoted on the secondary feeler and having a short arm pivotally connected with the primary feeler and having a long arm with a tooth on the under side thereof; and a controlling lever for the weft-replenishing mechanism upon which said long arm of said lever normally rests, a portion of the said controlling lever being in the path of said tooth, except when said lever is swung upwardly by the independent sliding movement of the primary feeler due to its encounter of the weft in substantial advance of the secondary feeler.

2. A feeler mechanism for a weft-replenishing loom having, in combination, a primary feeler and a secondary feeler, which both enter the shuttle and come in contact with the mass of weft therein; a guide in which the secondary feeler reciprocates; a spring acting on the secondary feeler to move it toward the lay; a guide on the secondary feeler within which the primary feeler has an independent sliding movement of its own, said primary feeler normally projecting rearwardly beyond the secondary feeler so as to contact with the weft in advance of the secondary feeler, and the contacting end of said primary feeler being thin so as to force the weft into a groove of a fluted weft-carrier; a lever pivoted on the secondary feeler and having a short arm pivotally connected with the primary feeler and having a long arm with a tooth on the under side thereof; and a controlling lever for the weft-replenishing mechanism upon which said long arm of said lever normally rests, a portion of the said controlling lever being in the path of said tooth, except when said lever is swung upwardly by the independent sliding movement of the primary feeler due to its encounter of the weft in substantial advance of the secondary feeler.

3. A feeler mechanism for a weft-replen-

- ishing loom having, in combination, a primary feeler and a secondary feeler, which both enter the shuttle and come in contact with the mass of weft therein; a spring acting on the secondary feeler to move it toward the lay; a guide on the secondary feeler within which the primary feeler has an independent sliding movement of its own, said primary feeler normally projecting rearwardly beyond the secondary feeler so as to contact with the weft in advance of the secondary feeler, and the contacting end of said primary feeler being thin so as to force the weft into a groove of a fluted weft-carrier; a lever pivoted on the secondary feeler and having a short arm pivotally connected with the primary feeler and having a long arm with a tooth on the under side thereof; and a controlling lever for the weft-replenishing mechanism, a portion of the said controlling lever being in the path of said tooth, except when said lever is swung upwardly by the independent sliding movement of the primary feeler due to its encounter of the weft in substantial advance of the secondary feeler.
4. A feeler mechanism for a weft-replenishing loom having, in combination, a primary feeler and a secondary feeler, which both enter the shuttle and come in contact with the mass of weft therein, said primary feeler normally projecting rearwardly beyond the secondary feeler so as to contact with the weft in advance of the secondary feeler and having a movement relatively to said secondary feeler; a controller for the weft-replenishing mechanism which is brought into action when the primary feeler is not moved independently of the secondary feeler; and a normally inactive adjustable auxiliary feeler fast on the secondary feeler which, when adjusted into active position, encounters a definite datum surface in advance of an encounter between the weft and the primary feeler.
5. A feeler mechanism for a weft-replenishing loom having, in combination, a primary feeler and a secondary feeler, which both enter the shuttle and come in contact with the mass of weft therein, said primary feeler normally projecting rearwardly beyond the secondary feeler so as to contact with the weft in advance of the secondary
- feeler, and having an independent movement relatively to said secondary feeler; and an adjustable auxiliary feeler which coöperates with a definite datum surface.
6. A feeler mechanism for a weft-replenishing loom having, in combination, a controller for the weft-replenishing mechanism; a spring-pressed reciprocating feeler support; an actuator for the controller movably mounted on said support; a weft-encountering primary feeler pivoted to said actuator; and a guide on the feeler support to limit the swinging movement of the primary feeler.
7. A feeler mechanism for a weft-replenishing loom having, in combination, a controller for the weft-replenishing mechanism; a reciprocating feeler support; an actuator for the controller movably mounted on said support; a weft-encountering primary feeler movably connected to said actuator; and a guide on the feeler support to limit the movement of the primary feeler relatively to the actuator.
8. A feeler mechanism for a weft-replenishing loom having, in combination, a reciprocating primary feeler which enters the shuttle; an auxiliary feeler which coöperates with a fixed datum surface carried by the lay; a feeler support for both of said feelers; a spring which moves the feeler support toward the lay, no part of the pressure applied to the spring by the lay being transmitted through the primary feeler; a controller for the weft-replenishing mechanism; and an actuator reciprocating with the feeler support and registering with said controller when the feeler mechanism is at rest, and said actuator being operatively connected to the primary feeler so that when said primary feeler encounters the weft the actuator is moved out of register with said controller, but when said primary feeler does not encounter the weft said actuator as it moves forward coöperates with said controller.

In witness whereof, I have hereunto signed my name in the presence of two subscribing witnesses.
